KNITTING MACHINE

William Henry Boaler and Albert Fairholme Guyler, Spondon, near Derby, England, assignors to Celanese Corporation of America, a corporation of Delaware

Application January 28, 1941, Serial No. 376,290
In Great Britain February 3, 1940

12 Claims. (CL 66—86)

This invention relates to knitting machines and is particularly concerned with warp knitting machines, that is, machines in which a large number of threads are knitted into a fabric, each thread running generally parallel to the length of the fabric.

In warp knitting machines, the large number of threads are led to the needles by means of guides, one for each thread, the guide being mounted in one or more guide bars and the guides in each bar being simultaneously and similarly operated. The operation of the guides involves two kinds of movement, firstly, movements parallel to the length of the series of needles by which the threads are knitted, either behind the needles so as to guide the threads from needle to needle behind the needle series, or in front of the needles to lap the threads under the beards of the needles, and secondly, movements across the line of the series of needles, from front to rear or from rear to front of the needles. After the threads are lapped under the beards of the needles the needles are simultaneously operated to produce a course of knitting before a further series of motions of the guides takes place. It is an object of the present invention to provide a machine and a method of knitting in which the guide movements outlined above are simplified.

According to the present invention, a method of warp knitting comprises knitting a series of warp threads all together on a series of needles into a succession of courses, engaging said series of threads constantly at a corresponding series of points above and in front of said series of needles in order to guide each warp thread to the appropriate needle in each course, moving said points between successive courses in a direction parallel to said series of needles, so as to guide said warp threads to different needles in different courses, and periodically, after the knitting of each course of fabric and immediately before the rising of the needles, engaging each thread between said series of points and the needle on which it was last knitted and pressing it across the length of said series of needles into engagement with the front of a needle preparatory to knitting the next course. Each thread may, in this manner, be brought into proper engagement with the needle on which it is to be knitted without the necessity of any motion across the line of the needles of the series of guides by which the warp threads are constantly engaged.

The means employed according to the invention for bringing about the necessary motions of

the threads comprise, in addition to the series of guides, disposed always above and in front of the needles, with which the threads are in constant engagement, a series of thread-engaging elements for coming into engagement with the threads at every course and for pushing them across the line of the needles. For this purpose, use may be made of the sinkers, ordinarily provided in the machine to act as a support for the fabric and to hold down the fabric each time the needles rise after knitting. In addition to the ordinary sinker throat (by which the holding-down is effected) a further throat or notch is provided above the level at which the fabric is formed, the sinker being made of sufficient depth to provide material for the formation of such a notch.

Since the guides by which the threads are constantly engaged do not need to be moved at right angles to the length of the needle series, the motions of these guides is very greatly simplified. This not only simplifies the mechanism by which the guides are actuated but also may be used to simplify the form of the guides themselves. For example, since the guides have not in any case to pass between a pair of adjacent needles in a motion across the line of the needles they need not be formed as a series of thin fingers, but can be, for example, a series of holes in a continuous plate or a series of grooves in a continuous bar. Thus, accuracy in the lengthwise positioning of the guide bar becomes of less importance, which in turn again simplifies the operating mechanism. Furthermore, greater freedom is allowed in the manner in which the threads may proceed to the guides. Where the guides have movements both from side to side and back and forth, it is necessary that the threads should reach them from substantially directly above. If the guides have only movements from side to side however, the threads may be led to them horizontally or obliquely from the rear. By these means, the whole design of the machine is simplified, and in particular the heavy warp beams from which the threads are supplied can be placed lower in the machine so that the centre of gravity of the machine is kept down. All these factors, viz. the simplification of the guide bar movement, the fact that more time in the cycle is available for it, and the reduced height of the machine, tend to reduce vibration in the machine, and, together with the reduced need for accuracy in the guide bar positioning, enable greater knitting speeds to be achieved.

The invention is applicable generally to warp

knitting machines in which all the needles are operated in the same way at the same time, but is most particularly applicable to flat warp knitting machines, in which the necessary sinker motions at right angles to the needle line may easily be effected. While the invention may be applied also to circular machines, some difficulties arise in connection with the necessary simultaneous radial motion of all the sinkers of such a machine. This difficulty, however, may be overcome by suitable mechanism, e. g. by the provision of pivoted or slideable sinkers and of an operating member in the form of a ring movable parallel to the axis of the machine and acting on the sinkers so as to cause them all to move inwards or outwards simultaneously.

By way of example, a particular method of carrying out the invention will now be described in greater detail with reference to the accompanying drawings in which:

Figure 1 is a diagrammatic front elevation,
Figure 2 is a diagrammatic side elevation, and

Figure 3 is a diagrammatic plan view showing needles, guides, sinkers and pressers in one position during knitting.

Figures 4 to 18 are five similar sets, of three figures each, showing five further stages, and

Figure 19 is a side elevational view, partly in section and partly broken away, of a warp knitting machine embodying our invention, and

Figure 20 is a partial front elevational view of the same.

Referring to Figures 1 to 3 the needles are indicated at 1 and the beards of the needles at 2. The sinkers are shown at 3 and it will be seen that each sinker is provided with a holding-down throat 4 and a thread engaging throat or notch 5. Two threads 6 and 7 are shown, each of these threads being representative of a series of threads, one for each needle, guided by thread guide bars 8 and 9. The thread guide bars 8 and 9 are disposed in front of the needles 1, i. e. on the beard side, and are capable of moving only in a direction parallel to the length of the series of needles 1, i. e. parallel to the plane of the paper in Figures 1 and 3 and at right angles to the plane of the paper in Figure 2. In Figure 1 the threads 6 and 7 are indicated as having been knitted on a needle particularly indicated at 10 and it will be seen that the thread 6 slopes upwards and to the left and thread 7 upwards and to the right from the needle 10 in consequence of the longitudinal motions of the guide bars 8 and 9 respectively. The sinkers 3 have been moved forward so as to engage each of the threads 6 and 7 at the level of the upper throat 5 of the sinker and to push the threads behind the line of the needles 1. It will be seen that the guide bar 9 has moved a greater distance than the guide bar 8 and in consequence of this, as shown in Figure 3, while the thread 6 crosses the needle line between the needle 10 and the adjacent needle to the left, the thread 7 crosses the needle line between the needles next and next but one to the right of needle 10. As a consequence of this, the needles, having risen as shown in Figure 2, have all risen in front of the thread 8 whereas one needle, the needle next to the right of the needle 10, has risen behind the thread 7.

As shown in Figures 4 to 6, the needles continue to rise so that, as their beards rise clear of the threads 6 and 7 the threads 6 and 7 are free to lie against the shanks 11 of the respective needles and under the beards 2. The re-

laxation of the threads 6 and 7 against the shanks 11 is clearly indicated in Figure 6. The further rise of the needle is accompanied by a further movement of the guide bars 8 and 9.

5 In Figures 7, 8 and 9 the needles have begun to fall and the threads 6 and 7 enter the beards of the appropriate needles. It will be seen from Figure 8 that the thread 7 shown therein is within the scope of the beard of the needle, although the needle visible in that figure is covering the needle by which the thread is actually engaged.

10 In Figures 10, 11 and 12 the downward movement of the needles is further continued and the beard 2 of the needle is closed by means of a presser 12 so that the point of the beard may pass inside the loop, indicated at 13, previously formed in the fabric. Instead of the usual plain presser bar, it is necessary to provide pressers 12 capable of passing between the sinkers 3 on account of the extra depth of the sinkers necessary for the formation of the notch 5.

15 In Figures 13 to 15 the sinkers 3 are withdrawn from the needles, and the needles, descending still further, are stretching the previously formed looped 13 in order to carry a new loop of thread through the old loop 13. At this stage, the guide bars 8 and 9 have begun their movement towards the left and right respectively, in the opposite directions to their former movements preparatory to knitting the next course.

20 In Figures 16 to 18 the needles have reached their lowest position and have drawn the new loop 14 through the old loop 13 while the sinkers 35 are moving forward again and have engaged the threads 6 and 7 at the level of their upper throats 5. The operations are then repeated, the threads 6 and 7 being moved in the opposite directions to those described above.

25 Since the point at which accuracy of spacing of the threads 6 and 7 is required is at the level of the sinker notches 5, and since the guide bars 8 and 9 are at some distance above this level, the accuracy required in the positioning of the guide bars 8 and 9 is reduced in proportion to their height above the fabric level. Accuracy 35 of the positioning of the notches 5 themselves is assured by the fact that the sinkers 3 are always in engagement between the needles 1, and 40 do not have to shift from one between-needle space to another.

45 From the above description it will be seen that the needle with which each thread of a guide bar is brought into such engagement may be a needle next to that on which it was last knitted, as in the case of the thread 6, or it may be some other needle e. g. the needle next but one to that on which it was last knitted as in the case of the thread 7. In the latter case, it is necessary that the thread 7 should not pass under the beard of the needle or needles intermediate between the needle 10 on which it was last knitted and the needle on which it is next to be knitted. This is brought about by a suitable selection of the height of the notch 5 by which the thread 7 is engaged between the needles 1 and the guides 9, and the extent to which the sinkers 3 are moved at right angles to the line of the needles 1, whereby each thread 50 is caused to pass behind the needle or needles it is not to be knitted on.

55 Where, as is particularly described above, two sets of threads such as 6 and 7 are knitted together, a 2-bar warp knitted fabric is produced, one bar, the threads 6, being knitted 1 x 1 and

the other, the threads 7, being knitted 2 x 2, to form a lockknit fabric. Either bar, however, may be omitted, to produce a single-bar 1 x 1 or 2 x 2 fabric, or a greater number of bars may be employed with independent motions, to give a multi-bar fabric.

Referring now to Figures 19 and 20, there is shown a warp knitting machine comprising a frame 15 on which the knitting elements are carried. Frame 15 also supports warp beams 16 and 17 from which threads 6 and 7, respectively, are drawn, the thread 6 passing over the tension bar 18 on its way to guide bar 8. The tension bar 18 is pivoted on bracket 19. Guide bars 8 and 9 are mounted for movement on and relative to fixed guide shaft 20 by means of levers 21 and carriers 21'. Needles 1 (10) are held in a needle bar 22 which is adapted to be moved up and down by a plurality of levers 22' secured to shaft 23 so as to swing in unison. The sinkers 3 are carried by rocker levers 24, mounted on sinker shaft 25 while pressers 12 are carried on rocker levers 26 mounted on presser shaft 27. The levers 22', 24 and 26 are operated in any suitable manner. For example, levers 22' which move the needle bar 22 are operated by means of a needle cam 22a through a follower arm 22b mounted on shaft 23. The needle cam is a mere eccentric, its center being displaced on the radius marked N. The rocker levers 24 which operate the sinkers 3 are given predetermined movement by a sinker cam 24a through follower 24b mounted on shaft 25. When the radius N reaches the end of the needle operating arm 22b, the radius marked S will have reached the end of the sinker operating arm 24b. At this stage, the needles are in their lowest position and are about to rise again while the sinkers have just finished their forward movement. It will thus be seen that the sinkers move forward immediately before the needles rise. The knitting of each course is complete before the needles reach their lowest position and immediately before the cam drop preceding the point on the sinker cam marked S.

Means are provided for moving the thread guides parallel to the length of the series of needles. This means comprises a plurality of levers 28 and 29 pivoted on a shaft 31 journaled in a bracket 32 on the frame 15. Levers 28 and 29 may be connected to the guide bars as by means of a push rod 33 which is shown connected to an angle-iron bracket 34 mounted on guide bar 9 and to the upper end of lever 28. A spring 35 is provided to minimize vibration. Reciprocating motion is given to the push rod 33 and the guide bar 9, as well as to guide bar 8, by means of pattern wheels 36 and 37 acting upon follower 38, one of which is fixed to each of levers 28 and 29. The follower 38 is caused to keep in contact with the profile of the pattern wheels 36 and 37 by means of springs 39 attached to brackets 41 fixed to cross bar 42 on frame 15. As will be appreciated, the profile of pattern wheels 36 and 37 may be altered to give any desired reciprocation to guide bars 8 and 9.

Having described our invention, what we desire to secure by Letters Patent is:

1. Method of warp knitting comprising knitting a series of warp threads all together on a series of needles into a succession of courses, each thread being confined to a small group of needles, engaging said series of threads constantly at a corresponding series of points above and in front of said series of needles in order

to guide each warp thread to the appropriate needle in each course, moving said points to and fro between successive courses in a direction parallel to said series of needles so as to guide said warp threads to and fro to different needles in different courses, and periodically, after the knitting of each course of fabric and immediately before the rising of the needles, engaging each thread between said series of points and the needle on which it was last knitted and pressing it across the length of said series of needles into engagement with the front of a needle preparatory to knitting the next course.

2. Method of warp knitting comprising knitting a series of warp threads all together on a series of needles into a succession of courses, each thread being confined to a small group of needles, engaging said series of threads constantly at a corresponding series of points above and in front of said series of needles in order to guide each warp thread to the appropriate needle in each course, moving said points to and fro between successive courses in a direction parallel to said series of needles so as to guide said warp threads to and fro to different needles in different courses, and periodically, after the knitting of each course of fabric and immediately before the rising of the needles, engaging each thread between said series of points and the needle on which it was last knitted and pressing it across the length of said series of needles into engagement with the front of a needle preparatory to knitting the next course.

3. Method of warp knitting comprising knitting a series of warp threads all together on a series of needles into a succession of courses, each thread being confined to a small group of needles, engaging said series of threads constantly at a corresponding series of points above and in front of said series of needles in order to guide each warp thread to the appropriate needle in each course, moving said points to and fro between successive courses in a direction parallel to said series of needles so as to guide said warp threads to and fro to different needles in different courses, and periodically, after the knitting of each course of fabric and immediately before the rising of the needles, engaging each thread between said series of points and the needle on which it was last knitted and pressing it across the length of said series of needles into engagement with the front of a needle preparatory to knitting the next course, the needle in engagement with the front of which each warp thread is pressed being, in some at least of the courses, separated by at least one needle from the needle on which said warp thread was knitted in the previous course.

4. Method of warp knitting comprising knitting a series of warp threads all together on a series of needles into a succession of courses, each thread being confined to a small group of needles, engaging said series of threads constantly at a corresponding series of points above and in front of said series of needles in order to guide each warp thread to the appropriate needle in each course, moving said points to and fro between successive courses in a direction parallel to said series of needles so as to guide said warp threads to and fro to different needles in different courses, and periodically, after the knitting of each course of fabric and immediately before the rising of the needles, engaging each thread between said series of points and the needle on which it was last knitted and pressing it across the length of said series of needles into engagement with the front of a needle preparatory to knitting the next course, the needle into engagement with the front of which each warp thread is pressed being, before some at least of the courses, adjacent to the needle on which said warp thread was knitted in the previous course.

5. Method of warp knitting comprising knitting a plurality of series of warp threads all together on a series of needles into a succession of courses, each thread being confined to a small group of needles, engaging each series of threads constantly at a corresponding series of points above and in front of said series of needles in order to guide each warp thread to the appropriate needle in each course, moving each of said series of points to and fro, independently of the other series, between successive courses in a direction parallel to said series of

needles so as to guide said warp threads to and fro to different needles in different courses, and periodically, after the knitting of each course of fabric and immediately before the rising of the needles, engaging each thread between said series of points and the needle on which it was last knitted and pressing it across the length of said series of needles into engagement with the front of a needle preparatory to knitting the next course.

5. Method of warp knitting comprising knitting two series of warp threads all together on a series of needles into a succession of courses, each thread being confined to a small group of needles, engaging each series of threads constantly at a corresponding series of points above and in front of said series of needles in order to guide each warp thread to the appropriate needle in each course, moving each of said series of points to and fro, independently of the other series, between successive courses in a direction parallel to said series of needles so as to guide said warp threads to and fro to different needles in different courses, and periodically, after the knitting of each course of fabric and immediately before the rising of the needles, engaging each thread between said series of points and the needle on which it was last knitted and pressing it across the length of said series of needles into engagement with the front of a needle preparatory to knitting the next course, the needle in engagement with the front of which each warp thread of one series is pressed being next but one alternately in opposite directions to the needle on which said warp thread was knitted in the previous course, and the needle into engagement with the front of which each warp thread of the other series is pressed being adjacent to the needle on which said warp thread was knitted in the previous course.

6. A warp knitting machine comprising a series of needles, a series of thread-guides disposed always above and in front of said needles, means for moving said thread-guides to and fro parallel to the length of said series of needles; a series of thread-engaging elements disposed between and alternating with the needles of said series of needles, and means for moving said elements in a direction across the length of said series of needles to engage the warp threads between the said needles and said guides immediately after the knitting of each course.

7. A warp knitting machine comprising a series of needles, a series of thread-guides disposed always above and in front of said needles, means for moving said thread-guides to and fro parallel to the length of said series of needles, a series of sinkers alternating with the needles, said sinkers having additional throats to engage the warp threads between said needles and said guides, and means for moving said sinkers in a direction across the length of said series of needles to effect said engagement immediately after the knitting of each course.

8. A warp knitting machine comprising a series of needles, a bar having a series of passages formed therein for the accommodation and guiding of the threads, said bar being dis-

posed always above and in front of said needles, means for moving said bar to and fro parallel to the length of said series of needles, a series of sinkers alternating with the needles, said sinkers having additional throats to engage the warp threads between said needles and said bar, and means for moving said sinkers in a direction across the length of said series of needles to effect said engagement immediately after the knitting of each course.

10. A warp knitting machine comprising a series of needles, a plurality of series of thread-guides disposed always above and in front of said needles, means for moving each series of thread-guides, independently of the remaining series, to and fro parallel to the length of said series of needles, a series of thread-engaging elements disposed between and alternating with the needles of said series of needles, and means for moving said elements in a direction across the length of said series of needles to engage the warp threads between the said needles and said guides immediately after the knitting of each course.

15. A warp knitting machine comprising a series of needles, two bars each having a series of passages formed therein for the accommodation and guiding of the threads, said bars being disposed always above and in front of said needles, means for moving said bars independently of each other, to and fro parallel to the length of said series of needles, a series of sinkers alternating with the needles, said sinkers having additional throats to engage the warp threads between said needles and said bars, and means for moving said sinkers in a direction across the length of said series of needles to effect said engagement immediately after the knitting of each course.

20. A warp knitting machine comprising a straight series of needles, a straight series of thread-guides disposed always above and in front of said needles, means for moving said thread-guides to and fro parallel to the length of said series of needles, a series of sinkers alternating with the needles, said sinkers having additional throats to engage the warp threads between the said needles and said guides immediately after the knitting of each course.

25. A warp knitting machine comprising a straight series of needles, two straight bars each having a series of passages formed therein for the accommodation and guiding of the threads, said bars being disposed always above and in front of said needles, means for moving said bars, independently of each other, to and fro parallel to the length of said series of needles, a series of sinkers alternating with the needles, said sinkers having additional throats to engage the warp threads between said needles and said bars, and means for moving said sinkers in a direction across the length of said series of needles to effect said engagement immediately after the knitting of each course.
